G. W. GAGE

DRILLING MACHINE

Filed June 7, 1926

Fig. 1.

P. T. Hickey.

WITNESS:

*George W. Gage,
INVENTOR
BY Victor J. Evans*

ATTORNEY

UNITED STATES PATENT OFFICE.

GEORGE WELLINGTON GAGE, OF PARNASSUS, PENNSYLVANIA.

DRILLING MACHINE.

Application filed June 7, 1926. Serial No. 114,374.

This invention relates to improvements in drilling devices, the general object of the invention being to provide means for giving a rotary shaft hammer-like blows as the shaft is being rotated so as to increase the cutting action of the bit carried by the shaft.

A further object of the invention is to provide means whereby the hammer means are rendered inactive whenever desired.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawing, in which:—

Figure 1 is an elevation, with parts in section.

Referring to the drawing, 1 indicates the rotary shaft which may be rotated from any suitable source and which is adapted to be suitably connected with a bit or other tool. 2 indicates a collar which is fastened to the shaft by a pin 3 and this collar is formed with the rack teeth 4. Each tooth is provided with a slanting wall and a straight wall. A collar 5, having similarly shaped teeth 6, is rotatably mounted on the shaft with its teeth engaging the teeth of the collar 2. A coiled spring 7 is placed on the shaft and has one end engaging a notch 8 formed in the collar 5 and its other end engaging a notch 9 formed in a collar 10 on the shaft, this collar 10 being held against rotary movement by one or more projections 11 thereon engaging a notch 12 formed in the boss 13 of the frame 14 of the device.

From the foregoing, it will be seen that as the shaft is rotated, the spring 7 will be held against rotation by means of the stationary collar 10 and this spring will in turn hold the collar 5 against movement. Thus as the collar 2 moves with the shaft, its teeth will ride up the inclined walls of the teeth 6 of the collar 5, thus pushing said collar 5 back against the pressure of the spring 7 until the teeth 4 of collar 2 pass over the inclined walls of the teeth 6 of collar 5, when the pressure of the spring 7 on collar 5 will throw the collar 5 forwardly against the collar 2 with considerable force and thus

produce a hammer-like blow on the collar 2 which is transmitted to the shaft. These blows come in rapid succession so that the cutting action of the tool is increased by these blows. When the hammer action is not desired, the collar 10 can be pushed forwardly on the shaft until its projection 11 leaves the recess 12 and a hole 15 in collar 10 registers with a hole 16 in the shaft so that a pin 17 can be placed in these holes to hold the collar 10 in this position. Then the collar 10, together with collar 5 and spring 7, will simply rotate with the shaft and no blows are given the shaft. When the pin is not in use, it can be attached by a chain 18 to a part of the frame 14.

While this invention is mainly designed for use on coal mining machines, it will, of course, be understood that it can be used on other machines where a hammering effect is to be produced on a rotary shaft.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. In combination with a rotary shaft, a toothed collar attached thereto, a second toothed collar loosely mounted on the shaft and having its teeth engaging the teeth of the first collar, a third collar on the shaft, means for holding the same against rotary movement, the second collar and the third collar having notches therein and a coiled spring on the shaft having its ends engaging the notches.

2. In combination with a rotary shaft, a toothed collar attached thereto, a second toothed collar loosely mounted on the shaft and having its teeth engaging the teeth of the first collar, a third collar on the shaft, means for holding the same against rotary movement, the second collar and the third collar having notches therein, a coiled spring on the shaft having its ends engaging the notches and means for fastening the third collar to the shaft, when desired, so that said collar will rotate with the shaft.

In testimony whereof I affix my signature.
GEORGE WELLINGTON GAGE.
